UNITED STATES PATENT OFFICE.

MICHEL HETT, OF MÜNSTEREIFEL, GERMANY.

PRIMING-MACHINE FOR KINDLING FIRES.

SPECIFICATION forming part of Letters Patent No. 445,261, dated January 27, 1891.

Application filed August 25, 1890. Serial No. 363,068. (No model.)

To all whom it may concern:

Be it known that I, MICHEL HETT, a subject of the King of Prussia and Emperor of Germany, and a resident of Münstereifel, in the Province of the Rhine, German Empire, have invented a new and useful Fuse or Priming-Machine for Kindling Fuels, of which the following is a clear and exact specification.

My invention relates to an apparatus in which a long horizontal flame of very high temperature is produced by dispersing petroleum, spirits, or the like by means of a continual jet of air, and blowing this combustible mixture through a small auxiliary flame. I attain this object by the apparatus illustrated in the accompanying drawings, in which similar letters denote similar parts throughout the different views.

Figure 1 is a longitudinal section taken on the line 1 2. Fig. 2 is a top view of the entire apparatus.

The liquid to be dispersed is contained in the reservoir *a*, closed by the cover *m*, which is provided with a small hole *n* for allowing air to enter the reservoir. The liquid is led to the point of dispersing by the tube *b*, attached to the reservoir *a* and bent at its extremity, so as to form an upwardly-extending tip *o*. A second tube is secured to tube *b* and extends over the end of *b*, bearing at its extremity a small case *d*, filled with sponge and closed by a sieve of wire-gauze. The sponge in the case *d* is soaked with the liquid contained in the reservoir *a*.

The jet of air necessary for carrying the apparatus into effect is generated by two rubber balls *e* and *f*, one of which *e* is made of thin and smooth rubber, and the other *f* of thick and tough rubber. Both rubber balls are provided with valves *g* and *h*, acting in such a manner that air may enter the balls through the short tubes *i* and *k*. The ball *e* serves for forcing air into the ball *f*, from which the air is blown through tube *l* in a constant and powerful jet. The tube *l*, crossing the reservoir *a*, terminates shortly before the tip *o* of tube *b*, and in forcing air through tube *l* and above the tip *o* the liquid is discharged at *o* and borne along with and by the jet of air in a finely-dispersed state.

The apparatus works as follows: The sponge

soaked with spirits and contained in the small case *d* is ignited, thus forming the auxiliary flame. The mixture of air and dispersed spirits is compelled to pass that flame, being ignited here and forming a long horizontal flame of enormous heat, which may be directed against the fuel to be kindled. In case petroleum is to be used for the apparatus, it has been found of greater advantage to blow a jet of air not mixed with the liquid petroleum through the auxiliary flame. The tube *b* may be provided near its tip with a faucet, closed when using petroleum and opened when using spirits.

The apparatus as described above is preferably employed for kindling the fuel of hearths and stoves.

For kindling the fuel of steam-boilers or the like, two modifications of larger dimensions, described hereinafter, have been constructed, one of those modifications intended for petroleum, the other for spirits.

That modification of the apparatus intended for petroleum is constructed as follows: The tube *l*, crossing the reservoir *a* and furnished with air from any blowing-machine, is of larger diameter than generally used. The end of the tube is divided into several short tubes of smaller diameter, all these short tubes being in the same horizontal plane. The case *d*, containing the sponge *i* for the auxiliary flame, is made so broad as to serve for the whole number of the short tubes at the same time, and the tube *c*, furnishing the sponge with petroleum, is connected directly with the reservoir *a*, the latter not being provided with a tube *b*.

The modification of the apparatus intended for spirits is constructed as follows: The tube *l*, crossing the reservoir, is of as large a diameter, as explained in the first modification, and also divided into a certain number of short and smaller tubes. A tube *b* directly in connection with the reservoir *a* is divided into as many small tubes as the tube *l*, and they are provided with tips in the same manner as described above. The case *d*, with its tube *c*, is secured to the tube *b* in the same way as explained in the description of Fig. 1, and the manner of working the apparatus is also similar to that of Fig. 1.

In both modifications a broad and long flame of enormous heat is produced, which is very much adapted for the rapid kindling of great quantities of fuel.

Having thus fully described the nature of my invention, what I desire to secure by Letters Patent of the United States is—

1. In a fuse or priming-machine for kindling fuels, the reservoir *a*, with the tube *l* and the cover *m*, in combination with a rubber ball *f*, having the valve *h* and attached to the reservoir by the tube *k*, the rubber ball *f* connected by the tube *i* with a second rubber ball *e*, having the valve *g*, for the purpose as described.

2. In a fuse or priming-machine for kindling fuels, the reservoir *a*, with the tube *l*, and provided with the tube *b*, having the upwardly-

extending tip *o*, and the parallel tube *c*, the latter furnished with a case *d*, filled with sponge or the like and closed by a sieve of wire-gauze, for the purpose as described.

3. In a fuse or priming-machine, the reservoir *a*, with the tube *l*, the latter terminating at one side in the rubber ball *f* and at the other shortly before the tip *o* of tube *b*, for the purpose as described.

In testimony whereof I have signed this specification in the presence of two subscribing witnesses.

MICHEL HETT.
